Des. 66,135

UNITED STATES PATENT OFFICE.

WILLIAM J. McLAUGHLIN, OF DOYLESTOWN, PENNSYLVANIA.

DESIGN FOR A BALL.

Application filed July 12, 1924. Serial No. 10,131. Term of patent 3½ years.

To all whom it may concern:

Be it known that I, WILLIAM J. McLAUGHLIN, a citizen of the United States, residing at Doylestown, in the county of Bucks and State of Pennsylvania, have invented a new, original, and ornamental Design for a Ball, of which the following is a specification, reference being had to the accompanying drawing, forming part thereof.

The figure is an elevation of a ball showing my new design.

I claim:—

The ornamental design for a ball, as shown.

W. J. McLAUGHLIN.
